UNITED STATES PATENT OFFICE.

VICTOR CHARLES BELL, OF NEW YORK, N. Y.

TOOTH-BRUSH.

No. 888,138.

Specification of Letters Patent.

Patented May 19, 1908.

Application filed December 10, 1906. Serial No. 347,209.

To all whom it may concern:

Be it known that I, VICTOR CHARLES BELL, a citizen of the United States, residing at the borough of Manhattan, in the city, county and State of New York, have invented certain new and useful Improvements in Tooth-Brushes, of which the following is a specification, reference being had therein to the accompanying drawing, forming a part thereof.

10 My invention relates to tooth-brushes, and has for its object the simultaneous thorough massaging of the gums and the effective brushing of the teeth longitudinally thereof.

15 It is now a known fact in dentistry that soft and bleeding gums will, if well massaged, become in a short time hard and firm, and that such massaging will keep them in a firm and healthy condition. In using the ordinary or any of the various forms of tooth-brushes now on the market the outer gums remain substantially untouched, because these brushes are too thick to enter between the gums and the overlying muscles of the mouth and face, rendering it impracticable to properly cleanse and massage the gums therewith. 20 Dental practitioners know that the teeth should be brushed longitudinally and not transversely, and yet such manipulation is difficult of attainment with the ordinary 25 tooth-brush.

30 My invention includes the provision, upon a tooth-rubbing or cleansing device or as it is generally known and hereinafter designated, a tooth-brush, of means for cleansing and massaging the gums.

35 My invention also includes, more specifically, a tooth-brush in which the cleansing head slopes or tapers transversely from about the usual thickness or length of bristles or other cleansing material at one side of the head to a comparatively thin edge at the other side of the head, the thin edge of the head being adapted to pass beneath the overlying facial tissues to reach the gums, and 40 the brush-head for this purpose being correspondingly wider so that the thicker portion thereof will at the same time act upon the teeth. The thin-edged head also permits a free movement longitudinally of the 45 teeth, or up and down, for more effectively cleansing the teeth and for massaging the gums, and my invention also includes the arrangement of such a tapered head as above 50 described in the form of a cross-head or in a 55 T-shape with the brush handle and with the

thin edge away from the handle, for the purpose of facilitating such longitudinal movement.

My invention further includes the employment of two different brushing or cleansing materials in the same brush-head, one of a nature peculiarly adapted to brush and cleanse the teeth, such, for example, as bristles of usual stiffness, and the other of a nature peculiarly adapted to cleanse and 60 massage the gums, such, for example, as soft rubber, or bristles of a soft and flexible quality.

In the accompanying drawings I have illustrated several embodiments of my invention, 70 all of which will now be particularly described by reference to such drawings, after which I will point out my invention in claims.

Figure 1 is an end view of the preferred construction. Fig. 2 is a face view of the 75 same, looking toward the rubbing surface. Fig. 3 is a side elevation of the same as viewed from the right of Fig. 2, but with the brush-head in section on a plane indicated by the line x , x , Fig. 2. Figs. 4 and 5 are similar 80 views illustrating modified constructions.

The back 1 and the handle 2 may be made of any suitable material and are preferably integral as shown, the handle extending perpendicularly from one edge of the back about 85 midway of the length of the back.

To permit of the gums being cleansed and massaged while the teeth are being cleansed, the back 1 is transversely tapered to a comparatively thin edge along its free edge or 90 opposite to the handle 2.

In the construction shown in Figs. 1, 2 and 3, a gum-massaging and gum-cleansing pad 3 of soft rubber is provided adjacent to the thin edge of the back 1 and may be secured 95 to the back by a suitable adhesive and is shown as further secured by dove-tailing, and is yet more firmly held in place by having a thin portion turned backward over the tapered edge of the back 1. The rubber pad 100 3 projects slightly beyond the tapered edge of the back 1 and this projecting portion, in connection with the turned back portion of the pad, assists in massaging the upper portions of the gums. For giving a better massaging action the massaging surface of the pad 3 may be provided with corrugations as 105 shown. The pad 3 is tapered or reduced in thickness toward the thinner edge of the back 1, the thinner edge of the pad being 110

sufficiently thin to enter to the full distance between the outer gums and the overlying facial tissues.

Tooth cleansing bristles 4 are carried by the back 1 adjacent to the thicker portion of the massage pad 3 and are fixed in the back 1 in the usual manner as shown. These bristles gradually taper or decrease in length toward the pad and away from the edge of the back 10 to which the handle is attached. The bristles are gradually reduced in length from the longest to the shortest so as to form a gradual slope or taper continuous with the slope or taper of the pad 3. Therefore, the entire 15 cleansing material, composed in this instance of the bristles 4 and the pad 3, is tapered transversely throughout its width toward the tapered edge of the back 1. This thin-edged or transversely sloping head permits 20 of a freer movement longitudinally to the teeth and such movement is facilitated or made more practicable and convenient by the arrangement of the handle 2 at right angles from or in a T-shape with the back 1, 25 the handle being also substantially perpendicular to the length of the tooth-cleansing bristles 4. The back 1 is curved as shown to correspond with the outer maxillary curvature.

30 The modified construction shown in Fig. 4 differs from that just described in that the massage pad is omitted and bristles are fixed in the back 5 along its full width, such bristles gradually tapering in length away from 35 the handle 7 and toward the thin edge of the back where they are shortest. The longer bristles 6 are of the usual stiffness, but the shorter bristles 8 are of softer quality in compensation for their shorter length and to obviate too great severity of action in their gum 40 massaging operation.

In the modification shown in Fig. 5 the shorter or gum-massaging bristles 9 are inclined outwardly or away from the tooth-cleansing bristles 10 and handle 11 and so as 45 to extend slightly beyond the thinner edge of the back 12, to more easily reach the upper portions of the gums. In other respects the construction and operation are the same as 50 described in reference to Fig. 4.

It is obvious that various modifications may be made in the constructions shown and above particularly described within the principle and scope of my invention.

55 I claim:

1. A tooth brush having, in combination, a head elongated so as to engage several teeth at once and wedge-shaped in transverse cross-section so as to present an operating surface acutely inclined to the back of the head, and a handle connected with the head at a point separated from the acute angle thereof so as not to interfere with the introduction of the head between the gums and 60 the lips.

2. A tooth brush having, in combination, a head elongated so as to engage several teeth at once and wedge-shaped in transverse cross-section so as to present an operating surface acutely inclined to the back of the head, and a handle connected with the head at a point separated from the acute angle thereof and arranged substantially perpendicular to the length of the head and at an acute angle with the working surface 70 thereof.

3. A tooth brush having, in combination, a head elongated so as to engage several teeth at once and wedge-shaped in transverse cross-section so as to present an operating surface acutely inclined to the back of the head, the head comprising gum-massaging means of comparatively yielding character forming the part of the working surface adjacent to the acute angle of the cross-section and tooth-cleansing means of comparatively firm character forming the rest of the operating surface, and a handle joining the head at a point separated from the acute angle thereof.

4. A tooth brush having, in combination, an elongated head comprising gum-massaging means of comparatively yielding character and teeth-cleansing means of comparatively firm character, and a handle connected with the head and substantially perpendicular to the length thereof.

5. A tooth brush having, in combination, a head comprising a back tapered toward one edge, gum-massaging means of a comparatively yielding character supported by the back adjacent to its thinner edge, and teeth-cleansing means of comparatively firm character supported by the back adjacent to its thicker edge, and a handle connected with the back at its thicker edge and substantially perpendicular thereto.

6. A tooth brush having, in combination, a head comprising a back tapered toward one edge, gum-massaging means of comparatively yielding character supported by the back adjacent to its thinner edge and tapering toward such edge, teeth-cleansing means of comparatively firm character supported by the back adjacent to its thicker edge and tapering toward the gum-massaging means, and a handle connected with the thicker edge of the back and substantially perpendicular thereto.

7. A tooth brush having, in combination, a head comprising a bristle portion for acting on the teeth and a soft rubber portion for acting on the gums, and a handle connected with the head and substantially perpendicular to the length of the head and of the bristles thereon.

8. A tooth brush having, in combination, a head comprising a back tapered toward one edge, teeth-cleansing bristles supported by the back adjacent to its thicker edge a

gum-massaging pad supported by the head adjacent to its thinner edge, and a handle connected with the thicker edge of the back and substantially perpendicular thereto.

- 5 9. A tooth brush having, in combination, a head comprising a back tapered toward one edge, a soft rubber gum-massaging pad supported by the back adjacent to its thinner edge and tapering toward such edge, and
10 teeth-cleansing bristles supported by the back adjacent to its thicker edge and taper-

ing in length toward the gum-massaging pad, and a handle connected with the back at its thicker edge and substantially perpendicular thereto.

15

In testimony whereof I have affixed my signature in presence of two witnesses.
